UNITED STATES PATENT OFFICE

165,764

DISK PLOW

Herman G. Klemm, Birmingham, Mich., assignor
to Harry Ferguson, Inc., Detroit, Mich., a corporation of Delaware

Application April 11, 1949, Serial No. 1,895

Term of patent 14 years

(Cl. D39—1)

To all whom it may concern:

Be it known that I, Herman G. Klemm, a citizen of the United States, residing at Birmingham, in the county of Oakland and State of Michigan, have invented a new, original, and ornamental Design for a Disk Plow, of which the following is a specification, reference being had to the accompanying drawing, forming a part thereof.

Fig. 1 is a side elevation of a disk plow, embodying my new design;

Fig. 2 is a plan view of the plow of Fig. 1; and
Fig. 3 is an end elevation of the plow of Fig. 1.

The dominant features of the design of the present invention reside in the portions shown in full lines in the accompanying drawings.

I claim:

The ornamental design for a disk plow, substantially as shown and described.

HERMAN G. KLEMM.
